US00D859618S

(12) **United States Design Patent** (10) **Patent No.:** **US D859,618 S**
Pinnell et al. (45) **Date of Patent:** **** Sep. 10, 2019**

(54) **HEATING APPARATUS CLIP**

(71) Applicant: **Pentair Water Pool and Spa, Inc.**,
 Cary, NC (US)

(72) Inventors: **Eric Louis Pinnell**, Holly Springs, NC
 (US); **Sean Michael McEwan**, Chapel
 Hill, NC (US); **James Lee Miller**,
 Sanford, NC (US)

(73) Assignee: **Pentair Water Pool and Spa, Inc.**,
 Cary, NC (US)

(**) Term: **15 Years**

(21) Appl. No.: **29/617,837**

(22) Filed: **Sep. 15, 2017**

(51) LOC (12) Cl. **23-03**

(52) U.S. Cl.
 USPC **D23/322**

(58) **Field of Classification Search**

USPC D23/259, 262, 365, 314, 316, 318, 322,
 D23/323, 341; D8/349, 354, 382
 CPC F16L 37/084; F16L 37/098; F16L 37/14;
 F16L 37/12

See application file for complete search history.

(57) **CLAIM**

The ornamental design for a heating apparatus clip, as shown and described.

DESCRIPTION

FIG. 1 is an isometric view of a top, front, and right side of a heating apparatus clip showing our new design;

FIG. 2 is a front elevational view of the heating apparatus clip of FIG. 1;

FIG. 3 is a rear elevational view of the heating apparatus clip of FIG. 1;

FIG. 4 is a right side elevational view of the heating apparatus clip of FIG. 1, the left side elevational view being a mirror image thereof;

FIG. 5 is a top plan view of the heating apparatus clip of FIG. 1; and,

FIG. 6 is a bottom plan view of the heating apparatus clip of FIG. 1.

1 Claim, 4 Drawing Sheets
